Primary Examiner — Mary Ann Calabrese*Assistant Examiner* — Catherine Ho(74) *Attorney, Agent, or Firm* — Andrus Intellectual Property Law, LLP(57) **CLAIM**

The ornamental design for a meeting table, as shown and described.

DESCRIPTION

FIG. 1 is a perspective view of a first embodiment of a meeting table.

FIG. 2 is a top view thereof.

FIG. 3 is a bottom view thereof.

FIG. 4 is a side view thereof.

FIG. 5 is an opposite side view thereof.

FIG. 6 is an end view thereof; and,

FIG. 7 is an opposite end view thereof.

The broken lines represent portions of the meeting table that form no part of the claimed design.
